UNITED STATES PATENT OFFICE.

PHILIPPE DE CLAMECY, OF BOSTON, MASSACHUSETTS, ASSIGNEE TO THE DE NEVEES TYPEWRITER CO., OF BOSTON, MASSACHUSETTS.

TYPE-WRITER PLATEN.

1,237,307.

Specification of Letters Patent. Patented Aug. 21, 1917.

Application filed May 16, 1916. Serial No. 37,804.

To all whom it may concern:

Be it known that I, PHILIPPE DE CLAMECY, a citizen of the United States, residing at Boston, county of Suffolk, Commonwealth 5 of Massachusetts, have invented certain new and useful Improvements in Type-Writer Platens, of which the following is a specification.

This invention relates to typewriters, and 10 particularly to the platens thereof with special reference to the deadening of those sounds resulting from the impact of the type.

It has been demonstrated that most of the 15 sound produced by a typewriter in operation is caused by the type striking the platen. The usual platens are simple rubber covered wooden tubes closed at both ends. Such platens have high-sound-reproducing qualities, first, because the core material, wood, is a very good natural conductor of sound owing to the close juxtaposition and practical continuity of its molecules, giving thus an increased repercussion of the sound 25 waves; and second, because of the drum-like construction where wooden tubes are used as cores.

The object of the present invention is to 30 appreciably reduce the sound produced by the type striking the platen. This object is attained by the use of a platen embodying in its structure materials of poor sound conductivity and which are so arranged and confined as to absorb and eliminate practically all of the sound waves set up by the striking type.

It has been attempted heretofore to produce a hollow or tubular platen, but the only structure of which I am aware provided for 35 a dense, practically integral shell substantially drum-like in structure and effect.

Briefly, my improved platen consists of a supporting shell or backing formed of strands which are substantially independent 45 of each other in relation to their sound conductivity or which in so far as they have contacting relation are opposed. This shell is further deadened by the substantial exclusion of air or the prevention of any substantial air space or chamber.

In practice, I preferably construct the shell or backing of woven strands of wire which take the place of the core heretofore employed in typewriter platens, and I have 55 found that the filling may be satisfactorily

accomplished by lightly filling with any suitable fibrous or filamentary material of sound absorbing nature.

The construction and effect of my platen is fully explained in the specification which 60 follows. In the drawings accompanying that specification, I have shown a form of platen which has been found highly satisfactory in use. Throughout this specification and in the drawings, like reference numerals are correspondingly applied, and in the drawings,—

Figure 1 is an elevation partially broken away of a typewriter platen in accordance 70 with my invention,

Fig. 2 is a view of the supporting rod or shaft of the platen removed,

Fig. 3 is a fragmentary view of the woven wire shell or backing and indicating by dotted lines different positions of the type 75 thereagainst, and

Fig. 4 is a diagrammatic view indicating type positions relative to the woven backing.

I have indicated at 1 the supporting rod or shaft of the platen. For such machines 80 as use a removable shaft, this rod may be fitted in a simple tube 1¹ of fibrous material extending centrally of the platen and having fastened thereon at suitable intervals a series of fiber disks 2. Where removability 85 is not required, this shaft may be solid.

Over the frame thus provided by the rod 1 and disks 2, I slip and secure a reticulated sleeve or core 3 which is preferably a woven seamless tubing.

While the core may be secured in position in any suitable manner, it is preferably rigidly attached to the two end disks of the series of disks 2. This permits the different end pieces or closures 3¹ of the different 95 makes of typewriters to be conveniently attached, and adapts my platen for use in all typewriters regardless of the specific type of platen closure used.

The woven tube may be soldered, but is 100 preferably woven as indicated in Fig. 1, in which each individual strand is represented as being substantially independent but interlaced and in dampering relation, and thus capable of interrupting and breaking the 105 continuity of sound transmission, thereby reducing the repercussion. The crossing strands of the wire backing are preferably at right angles to and parallel with the longitudinal axis of the platen respectively. 110

This affords a greater rigidity of structure without increasing its sound conductivity.

I have attempted to illustrate this action diagrammatically in Figs. 3 and 4. Fig. 3 shows the different portions of the netting 3 which may be struck by a type 6. Fig. 4 illustrates the dampering effect of the interlaced members of the woven backing. As will be evident, the vibration of any particular portion of either a transverse or a longitudinal strand is checked and stopped at practically its inception by the other strands which bear on it from above and below. This prevents vibrations of any considerable wave length from being set up or from extending over any considerable area, thus eliminating sound to a large degree.

The wire core 3 is provided with a rubber covering 4 drawn or formed over the wire but substantially independent thereof. The molecules of this covering have a very low responsiveness to sound waves, and assist to deaden the noises produced by the striking type.

25 The chambers defined by the woven shell 3 and disks 2 are filled with some fibrous material 5, the molecules of which are preferably of a non-vibrating nature. I find ordinary cotton wadding well adapted for this purpose in that it absorbs the sound and kills the repercussion entirely.

30 In assembling my platen, the cotton wadding is laid about the rod 1, and the wire core with its rubber covering is slipped over said rod in inclosing relation thereto.

35 From the foregoing, it will be seen that my platen practically deadens the sound waves produced by the shock of the type striking the platen. The sound of the type 40 against the paper or other surface being written upon, which surface is usually a good conductor of sound, can not be of course eliminated, but the sound caused by the type striking against the platen is so 45 absorbed and distributed as to be practically silenced.

Various modifications in the form and construction of my invention may obviously 50 be resorted to if within the limits of the appended claims.

What I therefore claim and desire to secure by Letters Patent is:

1. A typewriter platen consisting of an external impact receiving surface, a woven shell inclosed by said surface, but wholly free of connection therewith so that the individual strands of the shell are substantially free to vibrate, a bearing shaft, a

plurality of spaced elements thereon inclosed by said woven shell, and a finely divided filling. 60

2. A typewriter platen consisting of an external impact receiving surface, a woven backing inclosed by said surface, but wholly free of connection therewith so that the individual strands of the backing are substantially free to vibrate, a shaft, and a plurality of spaced elements of low sound conductivity thereon and inclosed by said backing. 65

3. A typewriter platen consisting of a shaft, a plurality of supporting elements, a woven wire backing inclosing said elements and having its individual strands substantially free to vibrate, and a filling of fibrous material within said backing and an external impact receiving surface supported on said backing. 70

4. A typewriter platen consisting of an external impact receiving envelop, and a cylindrical woven wire backing inclosed by said envelop but wholly free of connection therewith so that the individual strands of said backing are substantially free to vibrate. 80

5. A typewriter platen consisting of an external impact receiving surface, and a core of reticulated material inclosed by said surface but wholly free of connection therewith so that the individual strands of the core are free to vibrate to thereby break the continuity of transmission of sound waves. 85

6. A typewriter platen including an external impact receiving surface, and a core of woven wire inclosed by said surface, but wholly free of connection therewith so that the individual strands of said core are free to vibrate to thereby break the continuity of transmission of sound waves. 90

7. A typewriter platen including an external impact receiving surface, and a core of woven wire netting inclosed by said surface but wholly free of connection therewith so that the individual strands of the netting are substantially free to vibrate, said strands being disposed at right angles to each other, and one set being parallel to and the other set at right angles to the axis of rotation of the platen. 100

In testimony whereof I affix my signature in presence of two witnesses.

PHILIPPE DE CLAMECY.
